Specification of Letters Patent. Patented Aug. 12, 1913.

Application filed September 2, 1911. Serial No. 647,442.

To all whom it may concern:

Be it known that I, GEORGE H. GILMAN, a citizen of the United States, residing at St. Paul, Minnesota, have invented a certain 5 new and useful Improvement in Draft-Sills, of which the following is a full, clear, and exact description, such as will enable others skilled in the art to which it appertains to make and use the same, reference being had 10 to the accompanying drawings, forming part of this specification, in which—

Figure 1 is a top plan view of a pair of my improved draft sills, the same being applied to a pair of center sill members and 15 a portion of the body bolster and end sill of the underframe shown in dotted lines.

Fig. 2 is a vertical section taken on the line 2—2 of Fig. 1. Fig. 3 is a front elevation of the draft sills in position for use. Fig. 20 4 is a transverse section taken on the line 4—4 of Fig. 1. Fig. 5 is a transverse section taken on the line 5—5 of Fig. 1. Fig. 6 is a transverse section taken on the line 6—6 of Fig. 1. Fig. 7 is a transverse section 25 taken on the line 7—7 of Fig. 1.

This invention relates generally to car underframing, and more particularly to cast metal draft sills, which extend from the rear side of the end sill of an underframe, rearwardly across the top of the body bolster to a point considerably to the rear of said body bolster, and which draft sills are rigidly fixed to and serve as extensions for the shortened center sills of the underframe.

35 The principal objects of my invention are to provide simple, inexpensive cast metal draft sills, which can be readily applied to the underframe; to provide simple draft sills to which the draft rigging can be readily applied, and to provide a strong and durable construction which can be advantageously used to replace damaged wooden center sills on old cars; and to serve as portions 40 of the center sills of new cars.

45 To the above purposes my invention consists in certain novel features of construction and arrangement of parts hereinafter more fully described and claimed.

Referring by numerals to the accompanying drawings, 1 indicates the longitudinally disposed center sills of the car underframe, 2 the end sill, 3 the cast metal body bolster, 4 the draw-bar and 5 the draft rigging, all of which parts are of well known construction.

My improved draft sills, as shown, are fixed to the center sills 1 and extend from thence to the end sill 2, over the bolster 3 and serve as a support for the ends of the follower plates of the draft rigging 5, and 60 each sill is substantially L shaped in cross section, and comprises a vertically disposed web 6, and a horizontally disposed bottom flange 7. The rear portions of the webs 6 and the flanges 7 engage respectively against 65 the inner and under faces of the center sills 1, as shown in Figs. 1 and 7, and, by means of bolts 8 passing through said webs and flanges and the center sills, the draft sills are rigidly fixed to said center sills. The 70 ends of the center sills 1 bear directly against vertically disposed plates 9, which are formed integral with the draft sills adjacent their rear ends, and formed integral with the forward ends of said sills are vertically disposed plates 10, which bear directly against, and are fixed to, end sill 2. Lugs 11 are formed on the front faces of 75 these plates 10, and are seated in corresponding recesses formed in the rear side of the 80 end sill.

Formed integral with the upper edge of the vertical web 6 of each draft sill is a horizontally disposed, longitudinally extending flange 12, and a corresponding flange 85 13 is formed integral with the lower edge of the web 6, which flange 13 preferably occupies the same horizontal plane with the flange 7.

Formed integral with the outer face of the 90 web 6, and extending from the plate 9 to the plate 10, is a horizontally disposed flange 14, which materially strengthens the central portion of the draft sill, and serves as a support for a wooden filler block 15, to 95 which the car flooring 16 is fixed.

The horizontally disposed flanges 7 and 13 bear directly upon the top plate of the bolster 3, and the draft sills are detachably fixed to said bolster by means of blocks 17 100 applied to the underside of the draft sills, and which blocks are held in place by means of bolts 18, or like fastening devices. The forward ends of these blocks are provided with lips 19, which engage beneath the 105 edges of the top plate of the bolster, and the rear ends of these blocks bear directly against transversely disposed lugs 20 formed integral with the underside of the flanges 7 and 13. That portion of the draft sill im- 110

mediately above the top plate of the bolster can be recessed, as shown, in order to accommodate the annular rib, which is usually formed on the top plate of the bolster 5 around the king pin opening therein.

21 designates a spacing block arranged between the central portions of the draft sills, and held in position by transversely disposed bolts 22, which pass through the 10 vertically disposed webs 6. Formed integral with the forward portions of the webs 6 is a series of lugs 23, and the recesses 24, between said lugs, serve as pockets for the end portions of the follower plates of the 15 draft rigging 5.

25 designates removable straps or plates, which are bolted to the undersides of the lugs 23, and which straps or plates extend beneath the pockets 24, thereby supporting 20 the end portions of the follower plates of the draft rigging. These straps or plates 25 are made removable in order that the draft rigging 5 may be readily placed in position, or removed therefrom as desired.

25 Draft sills of my improved construction are comparatively simple, and inexpensive, can be readily applied for use, for a very strong and rigid construction between the center sills, the bolster and end sill and said 30 draft sills can be utilized in connection with damaged wooden center sills of old cars, as well as upon the ends of the center sills of new cars.

It will be readily understood that minor 35 changes in the construction and arrangement of parts of my improved draft sills may be made without departing from the spirit of my invention, the scope of which is set forth in the appended claims.

40 I claim,

1. In a car underframe, a pair of independent draft sills overlying and fixed to the body bolster of the underframe, transverse plates on the rear portions of said 45 draft sills against which the ends of the center sills of the car underframe engage, transverse plates on the forward ends of the draft sills, which last mentioned plates bear against the inner face of the end sill of the 50 car underframe, lugs on said last mentioned plates, which lugs engage in recesses in the end sill, a spacing block between the central portions of the draft sills, and fastening devices seated in said draft sills and the spacing block.

2. The herein-described draft sill comprising an elongated flanged member adapted to overlie a car underframe body bolster, the rear end of which draft sill is adapted to engage and be fixed to one of the underframe center sills, a plate integral with the forward end of the draft sill, which plate engages the inner face of the underframe end

sill, and a lug projecting forwardly from said plate, which lug is adapted to engage 65 in a recess in the end sill.

3. In a car underframe, a pair of independent draft sills overlying and fixed to the body bolster of the car underframe, transversely disposed plates on the rear portions of said draft sills, which plates abut the ends of the center sills of the underframe, transversely disposed plates on the forward ends of said draft sills, which last mentioned plates abut the end sill of the car underframe, horizontally disposed flanges on the draft sills, between the transversely disposed plates and forwardly projecting lugs on the plates at the forward ends of the draft sills.

4. In a car underframe, a pair of independent draft sills overlying and fixed to the body bolster of the underframe, transverse plates on the rear portions of said sills against which the ends of the center 85 sills of the car underframe engage, transverse plates on the forward ends of the draft sills, which last mentioned plates bear against the rear faces of the end sill of the car underframe, and lugs on said last mentioned plates, which lugs engage the recesses in the end sill.

5. The herein-described draft sill comprising an elongated member substantially L-shaped in cross section, a transverse plate 95 formed on the rear portion of said draft sill against which the end of the center sill engages, a transverse plate on the forward end of said member, which last mentioned plate abuts against the end sill of the car underframe, a lug on said last mentioned plate, which lug engages in a recess in the end sill, and a horizontally disposed flange on the body of the draft sill between the transversely disposed plates.

6. The herein-described draft sill comprising a member which is substantially L-shape in cross section, a transversely disposed plate integral with the forward end of said member for abutting the end sill of the car underframe, a forwardly projecting lug on said plate, which lug is adapted to engage in a recess in the end sill, a transversely disposed plate integral with the rear portion of said draft sill for abutting the end 110 of one of the center sills of the car underframe, and a horizontally disposed flange 115 integral with the draft sill and arranged between the transversely disposed plates.

In testimony whereof I hereunto affix my 120 signature in the presence of two witnesses, this 28th day of August, 1911.

GEORGE H. GILMAN.
